CAMPING TRAILER

Charles F. Lawley, R.D. 5, Shavertown, Pa. 19603

Filed Jan. 18, 1966, Ser. No. 665

Term of patent 14 years

(Cl. D14—3)

FIG. 1.

FIG. 2.

FIG. 3.

FIG. 4.

FIG. 5.

FIG. 6.

FIG. 7.

FIG. 8.

FIG. 9.

FIGURE 1 is a top plan view of a camping trailer in traveling condition, showing my new design;

FIG. 2 is a side elevational view of the camping trailer as shown in FIG. 1;

FIG. 3 is a front elevational view of FIG. 1;

FIG. 4 is a partial rear elevational view of FIG. 1;

FIG. 5 is a top plan view of the trailer shown in FIG. 1, but in camping condition;

FIG. 6 is a bottom plan view of FIG. 5;

FIG. 7 is a side elevational view of FIG. 5;

FIG. 8 is a side elevational view, similar to FIG. 7, but of the opposite side of the trailer; and

FIG. 9 is a front elevational view of FIG. 5.

I claim:

The ornamental design for a camping trailer, substantially as shown and described.
